UNITED STATES PATENT OFFICE.

LEWIS FERRY MOODY, OF PHILADELPHIA, PENNSYLVANIA.

ROTARY PUMP WITH ADJUSTABLE GATE.

1,322,810.

Specification of Letters Patent. Patented Nov. 25, 1919.

Application filed June 10, 1919. Serial No. 303,132.

To all whom it may concern:

Be it known that I, LEWIS FERRY MOODY, a citizen of the United States, residing at Philadelphia, in the county of Philadelphia and State of Pennsylvania, have invented 5 certain new and useful Improvements in Rotary Pumps with Adjustable Gates, of which the following is a specification.

The principal objects of my invention are 10 to provide new and improved means for controlling the performance of a rotary hydraulic pump and to provide a method of moving water against an opposing head for which such a pump may be employed. Another 15 object of my invention is the maintenance of high efficiency in a rotary hydraulic pump when the pump is operated at various rates of discharge, that is, the improvement of the efficiency of the pump when discharging 20 quantities of water greater or less than the normal or designed quantity. Still another object is the provision of a regulating or controlling valve for a pump which can be conveniently and quickly operated 25 by means of fluid pressure. All these objects and others will be appreciated upon consideration of a limited number of specific examples of practice under my invention which are disclosed in the following 30 specification and claims taken with the accompanying drawings. It will be understood that modifications may be made within the scope of my invention.

Referring to the drawings,

35 Figure 1 is a vertical section of a vertical shaft pump embodying my invention.

Fig. 1^a shows a detail of Fig. 1.

Fig. 2 is an axial section of a horizontal shaft pump illustrating a different type of 40 pump and gate control means and

Fig. 3 is an axial section of a different type of pump embodying my invention.

Referring to Fig. 1, the power shaft 11 in the bearing 12 and passing through the 45 packing box 13 carries the impeller 14 with the vanes 15 and shroud ring 16. The inflow conduit 32 leads up vertically to the impeller, which discharges through the diffuser 19 into the spiral chamber 18 ending 50 in the flange 17, which may be attached to any suitable conduit or receiving tank.

The stationary pump frame 33 supports the spiral casing 18 and an annular cylinder 23, of which the outside wall is 20, the inside 55 wall 21 and the annular head 22. Within

this annular cylinder 23 is a corresponding plunger 24 with the annular head 25 forming the upper face of the diffuser 19. This plunger is shown in Fig. 1 in the position corresponding to the operation of the pump 60 at full discharge. For reduced output of the pump, the plunger 24 may be lowered as will be explained more in detail presently. The inner corner of the head 25 is slightly rounded off at 26 to facilitate such a part 65 gate operation of the device.

The plunger 24 is moved by fluid pressure admitted to the cylinder 23 through either pipe 29 or 30. Attached to the plunger 24 is a restoring rod 40, which goes through a 70 valve chamber 39 (Fig. 1^a) in the valve casing 41 having the cylindrical liner 42. The valve member 43 has the pistons 44 and 45 adapted to control the valve ports as shown in the drawing. This valve member 43 extends outside of the valve casing 41 at 46, where it rotatably carries hand wheel 51 held by a key 48 in slots 47 and 49, so that rotation of hand wheel 51 adjusts valve 43 75 relatively to rod 40 and this adjustment is indicated on scale 58 on extension 57 passing through sleeve 54 and cap 55 and having a tight sliding fit in the former by packing 56.

The adjustment of the gate 24 corresponding 80 to the setting of hand wheel 51 on scale 58 will automatically be maintained by the restoring device for example as follows: Should the gate 24 move down from its adjusted position valve member 43 will also 85 be moved down admitting pressure from pipe 27 and port 60 to pipe 30 and connecting pipe 29 to exhaust 61, 28 to raise the gate; conversely upward movement of the gate from adjusted position will connect 90 pipe 29 to the pressure fluid and pipe 30 to the exhaust to lower the gate back to set position. The space below 44 is connected with 61 by a passage not shown. The hand wheel 51 also serves to control the gate 100 movements, for instance to close the gate 24 the hand wheel 51 will be rotated counter-clockwise, thus causing the valve member 43 to move up relatively to the rod 40. Such movement will connect pressure pipe 27 with the ports uncovered by valve member 45 and admit the pressure fluid through the conduit 29 to close the gate. The consequent movement of the restoring rod 40 will close 105 the port under the valve member 45 and the 110

gate 24 will be held at the new position of adjustment determined by the extent of movement of the hand wheel 51.

In full gate operation the parts will have 5 the adjustment shown in Fig. 1. The impeller vanes 15 will receive the water from the inflow conduit 32, drive it with relatively high velocity into the diffuser 19 and thence with reduced velocity into the spiral 10 collector 18, where the remainder of its velocity energy will be converted with as little loss as possible, into static head. If it is desired to reduce the quantity of water being pumped, the plunger will be lowered to 15 a proper degree under the control of the hand wheel 51.

The embodiment of my invention shown in Fig. 2 differs from that of Fig. 1 in that the pump axis is horizontal instead of vertical and the plunger location is on the intake side of the impeller instead of on the side opposite to the intake. The plunger 24 in the Fig. 2 pump is controlled by hydraulic pressure supplied through the pipe 27 and regulated by the four-way valve 31. This valve is shown in Fig. 2 in position to move the plunger 24 to the left by admitting pressure fluid from the pipe 27 through the pipe 30 to the right end of the cylinder 23. 20 At the same time that the pressure is admitted to the right end, the pipe 29 from the other end is connected by the valve 31 to the exhaust conduit 28. When the plunger 24 has been moved to any desired point, an 25 eighth turn of the valve 31 either way will close all the ports and hold that stage of adjustment. To move the plunger 24 to the right the valve 31 will be given a quarter turn from the position shown in Fig. 1, so 30 as to connect the pressure pipe 27 to the conduit 29 at the left end of the cylinder 23 and also to connect the exhaust conduit 28 with the pipe 30 at the right end of the cylinder 23.

45 In the embodiment of my invention shown in Fig. 3, the plunger gate is on the lower side of the diffuser instead of on the upper side as shown in Fig. 1. The impeller vanes 15 carry no shroud ring. The direction of flow through the diffuser 19 is not in a common plane, but is conical as will readily be seen by comparing Fig. 3 with Fig. 1. The plunger 24 has its inside cylindrical wall on the inner side of the inside cylinder wall 21 50 so that as the water flows around the corner 26, it is never sharply deflected and no pocket can be formed by the rounded corner 26 passing within any part of the casing.

In Fig. 3, the gate 24 is shown at normal full gate position by the full lines, but it is designed for operation at "over-gate" adjustment, if desired, as indicated by the dotted lines. In this case, there will be an annular clearance space around the 65 outer ends of the impeller vanes 15, but the

water will be dragged along through this annular clearance space by the stream nearer the axis which is moved in a more positive manner by the impeller vanes 15. The action will be somewhat on the principle of 70 the ejector by which one stream of fluid is caused to pick up and impart its motion to another body of fluid. The operation under over-gate conditions as described may be advantageous when it is desired to move an 75 unusually large volume of water at somewhat less than the usual head, and when the maintenance of the full normal efficiency of operation is not important under such 80 usual conditions.

It will be seen that I have provided a pump in accordance with my invention, which will operate to give widely different discharge rates without undue sacrifice of efficiency. When the plunger gate is wide 85 open, the water is delivered from the margin of the impeller into the diffuser space 19 with a considerable velocity energy. When the plunger gate is nearly closed, the impeller forces the water through the comparatively narrow diffuser with a velocity as high as before, but in diminished volume. The water flows around the rounded corner 26 of the plunger head 25 with smooth lines 90 of flow in a manner somewhat similar to the 95 flow of a jet from an orifice. The diminished output of the pump under part-gate conditions means a correspondingly diminished requirement of power, because the reduced output is obtained without throttling 100 in such a way as to set up eddies or otherwise occasion loss of energy.

An advantage of the arrangement of this invention is the provision of a well formed diffusion space at all degrees of opening of 105 the plunger gate, so that in all positions there will be ample space for a gradual reduction of velocity and conversion of velocity head into pressure head. Moreover, as the opening is made smaller, the loss 110 which would otherwise be caused by sudden enlargement at the outer periphery of the plunger is offset by the relatively greater efficiency of diffusion due to the greater ratio of length to width of the diffusion 115 space. For when the plunger is partially closed, the length of passage traversed by the water is much greater in proportion to its width than when the plunger is open, and the conversion of velocity head into 120 pressure head will be more efficiently effected in the part-gate position. Therefore in all positions of the plunger the diffuser has 125 high efficiency. The water traverses this space 19 in long spiral paths and its whirl component is reduced in inverse proportion to the radius. When the water reaches the outer periphery of the plunger, which is the outer periphery of the diffuser, and enters the spiral casing, its velocity is 130

greatly reduced both in its radial and whirl components. Thus under conditions of reduced discharge the loss due to the casing being too large in cross section to suit the 5 whirl component will be largely overcome by the conversion of whirl component within the diffusion space.

Another advantage of my invention is the simplicity and ruggedness of the structure, 10 especially as compared with wicket gates or adjustable guide vanes, which involve considerable mechanism and are not practicable for providing an adjustable diffusion space.

15 I claim:—

1. In a rotary pump, an impeller, a diffuser around said impeller with substantially parallel annular walls, and a conduit around said diffuser, one of said walls of 20 the diffuser being movable to or from the other and relatively to the adjacent edge of the discharge space of said impeller to adjust the capacity of the pump.

2. In a rotary pump a rotary impeller, 25 a plunger gate surrounding said impeller and displaceable axially with relation to the edge of the discharge space of said impeller to adjust the capacity of the pump and means to move said gate by fluid pressure.

3. In a rotary pump, a plunger gate displaceable axially to adjust the capacity of the pump, a cylinder and coacting piston, one fixed and the other connected with said 35 gate, and means at each end of said cylinder to introduce fluid pressure between said piston and the corresponding head of the cylinder to move said gate in either direction.

40 4. In a rotary pump, an impeller having passages of constant cross-section, and a gate close to and coaxial with the impeller but separate therefrom and movable axially to adjust the cross section at said gate of 45 the stream through the pump.

5. In a rotary pump, an impeller having passages of constant cross-section, a diffuser adjacent thereto, and means to adjust the diffuser by varying its cross section 50 across the lines of flow, thereby to adjust the capacity of the pump.

6. In a rotary pump, an impeller, and a coaxial gate closely adjacent to the impeller and adapted to be moved relatively 55 to the adjacent edge of the discharge space of said impeller.

7. The method of adjusting the capacity of a rotary pump having a diffuser and impeller which consists in varying the cross 60 section of the diffuser across the lines of flow therethrough while maintaining the cross section of the passages within the impeller unchanged.

8. The method of adjusting the capacity 65 of a rotary pump which consists in cutting

off to a suitable degree the cross section of the stream across the flow lines, at points close to the impeller on its delivery side without changing the cross sectional area of the passages within the impeller.

9. In a rotary pump, an impeller having passages of constant axial width, a diffuser adjacent thereto, and means to vary the axial width of the diffuser to adjust its cross section across the lines of flow, thereby to adjust the capacity of the pump. 70

10. In a rotary pump, an impeller, and a coaxial gate closely adjacent to the impeller and displaceable in an axial direction relatively to the adjacent edge of the discharge 80 space of said impeller to adjust the capacity of the pump.

11. The method of adjusting the capacity of a rotary pump having an impeller and a diffuser which consists in varying the cross 85 section of the diffuser across the lines of flow therethrough without changing the cross section of the passages within the impeller.

12. The method of adjusting the output 90 of a rotary pump having a diffuser without sacrifice of efficiency which consists in varying the capacity of the diffuser by relative movement of its guiding surfaces without changing the cross sectional area of the 95 passages within the impeller.

13. The method of adjusting the capacity of a rotary pump having an annular outward flow diffuser surrounding the impeller which consists in varying the width of the 100 diffuser in an axial direction without changing the cross sectional area of the passages within the impeller.

14. In a rotary pump, an impeller, a diffuser around said impeller with substantially parallel annular walls and a spiral conduit around said diffuser, one of said walls of the diffuser being movable to or from the other and relatively to the adjacent edge of the discharge space of said 105 impeller to adjust the capacity of the pump.

15. In a rotary pump, an impeller, a diffuser around said impeller with substantially parallel annular walls, and a conduit around said diffuser, one of said walls of the diffuser being movable to or from the other and relatively to the adjacent edge of the discharge space of said impeller to adjust the capacity of the pump, said movable wall having its edge toward 115 the impeller rounded off to give smooth lines of flow around it.

16. In a rotary pump, an impeller, a diffuser around said impeller, an annular cylinder adjacent to said diffuser, and a corresponding piston therein, one wall of said diffuser being connected to said piston by a cylindrical barrel. 125

17. In a rotary pump, an impeller, a diffuser around said impeller, an annular cyl- 130

inder adjacent to said diffuser, a corresponding piston therein, one wall of said diffuser being carried by said piston, pressure supply conduits to the ends of said cylinder, and valve means to move said piston either way or hold it at any desired adjustment entirely by the admission of fluid pressure to either side of the piston.

18. In a rotary pump, an impeller, a diffuser around said impeller, an annular cylinder adjacent to said diffuser, a corresponding piston therein, one wall of said diffuser being carried by said piston, pressure supply conduits to the ends of said cylinder, and valve means to move said cylinder either way and to automatically maintain it at any desired adjustment or restore it if displaced.

19. In a pump the combination with guiding walls forming a passage directing the flow of fluid, of impeller vanes extending only partly across said passage, said walls being formed to cause the flow through the remainder of the passage to be drawn along by the flow through said vanes.

20. In a pump the combination with guiding walls comprising a movable gate and forming a passage directing the flow of fluid, of impeller vanes extending only partly across said passage, said walls being formed to cause the flow through the

remainder of the passage to be drawn along by the vanes and said gate being movable to direct substantially all of the fluid 35 through said vanes.

21. In a pump the combination with an impeller and inlet and discharge passages, of a plunger gate in said discharge adjustable relatively to the adjacent edge of the 40 discharge space of said impeller and having a normal position for full load, said parts being formed to permit said gate to be moved to give either greater or less discharge than that for said normal position. 45

22. In a rotary pump, an impeller, a diffuser around said impeller, an annular cylinder adjacent to said diffuser, a corresponding piston therein, one wall of said diffuser being carried by said piston, pressure supply conduits to the ends of said cylinder, and valve means to move said cylinder either way and to automatically maintain it at any desired adjustment or restore it if displaced. 50

23. The method of regulating the capacity of a rotary pump having an impeller and a discharge opening therefrom, comprising varying the cross section of said discharge opening adjacent said impeller 60 with relation to the cross section of the passages of said impeller. 55

LEWIS FERRY MOODY.
